PROCESS FOR DEMETALIZING HYDRO-CARBON OILS

Herman Bieber, Linden, and Theodore B. Simpson, East Orange, N.J., assignors to Esso Research and Engineering Company, a corporation of Delaware

Filed May 13, 1958, Ser. No. 734,912
20 Claims. (Cl. 208—253)

The present invention relates to the upgrading of hydrocarbon oils and more particularly relates to an improved process for the removal of innate organo-metallic contaminants from residual hydrocarbon oils boiling in excess of about 1000° F.

Organic-metallic contaminants, principally complex iron, nickel, and vanadium compounds, are found as innate constituents in practically all crude oils and may be present therein in concentrations of 200 pounds per 1000 barrels of oil or higher. Upon fractionation of the crudes, these contaminants are concentrated in the residua which normally have initial boiling points of about 1000° F. Such residua are conventionally used as heavy fuels and it has been found that the contaminants therein have a very adverse effect upon the combustion equipment in which the residua are burned. The contaminants not only form ash which leads to slagging and the formation of deposits upon boiler tubes, combustion chamber walls, and gas turbine blades, but also attack the refractories which are used to line boilers and combustion chambers and severely corrode boiler tubes and other metallic surfaces with which they come into contact at high temperatures. Although there have been many suggestions in the past as to methods which might be used to remove metallic contaminants from high boiling residua, no wholly satisfactory process for accomplishing this has been available heretofore.

The present invention provides a new and improved method for removing innate organo-metallic contaminants from hydrocarbon oils boiling in excess of about 1000° F. in accordance with which the oils are contacted in liquid phase with a fused alkali metal hydroxide in order to modify the properties of the complex organo-metallic compounds present therein and permit their physical separation from the product oil. It has been found that treatment with fused alkali metal hydroxides in accordance with the invention results in a decrease in the oil solubility of the metallic compounds and a corresponding increase in their water solubility such that substantial quantities of the contaminants can be removed by water washing, filtering or similar treatment of the oil. Selectivity of the reaction between the fused hydroxides and the metallic contaminants is high and excellent yields of demetalized oil are obtained. The process is additionally beneficial in that it also removes some undesirable sulfur and acidic materials present in the oil which would otherwise have to be taken out by further processing steps. The invention thus provides a process for upgrading residua containing metallic contaminants which is highly effective, easily carried out, and economically attractive.

The process of the invention can best be understood by first considering the nature and properties of the metallic contaminants which are found in petroleum residua. These contaminants are innate constituents of crude oil

2

and are nonvolatile at temperatures below about 1050° F., hence they are not present to any appreciable extent in distillates conventionally recovered by fractionating crude oil. Analyses have shown that some of the contaminants are complex organic compounds of the porphyrin type in which a central atom of iron, nickel, vanadium or a similar metal is surrounded by four pyrrole rings interconnected by methene linkages. Various substituents including alkyl chains, alkylene groups, and carboxylic radicals may be attached to each of the pyrrole rings at several positions. In some cases, two or more such molecules apparently polymerize to give an even more complex structure which is nonvolatile at temperatures of 1300° F. or higher.

10 In treating these complex molecules with fused alkali metal hydroxides in accordance with the process of the invention, it may be that the alkali metal hydroxides react with acid radicals present as side chains on some of the organo-metallic molecules to form alkali metal salts. 15 Such salts are less oil-soluble than the unmodified contaminants and, to some extent, can therefore be separated from the oil by filtration, centrifugation or similar procedures. Because the alkali metal salts have greater 20 water solubility than the unreacted organo-metallic compounds, water washing removes substantial quantities of the contaminants, yielding an oil of greatly reduced 25 metals content. On the other hand, it may be that the hydroxides completely degrade some of the contaminants and form water-soluble inorganic compounds rather than 30 alkali metal organo-metallic salts. There is considerable support for this latter view. Other mechanisms may also be postulated.

The alkali metal hydroxides suitable for use in carrying out the process of the invention include fused sodium 35 hydroxide, potassium hydroxide, lithium hydroxide, and the like. Because of their particular effectiveness, sodium hydroxide and potassium hydroxide are the preferred reactants. In order to facilitate handling of the fused hydroxides and to permit treatment at temperatures below 40 those at which degradation of the oil due to thermal cracking occurs, it is usually preferred to employ eutectic mixtures of two or more different hydroxides, particularly mixtures of sodium and potassium hydroxide, which have 45 melting points somewhat lower than those of the pure compounds. By employing such mixtures, hydroxide compositions which are liquid at temperatures as low as 325° F. or somewhat lower may be obtained. Similar low melting eutectic mixtures can be obtained by adding a minor amount of sodium carbonate to sodium hydroxide, a mixture containing about 8% Na_2CO_3 and 92% NaOH having a melting point of about 510° F. for example. It is generally preferred to treat the oil with from about .01 to about 2 volumes of alkali metal hydroxide per volume of oil. Treatment with from about 0.1 to 55 about 1 volume per volume is generally preferred.

In carrying out the process of the invention, the oil from which the metallic contaminants are to be removed is treated with the fused alkali metal hydroxide or eutectic mixture at a temperature in the range of from about 325 to about 700° F. Thermal cracking of the oil and product degradation due to undesirable side reactions of the hydroxide with constituents of the oil other than the metallic compounds begin to take place at temperatures between about 600 and 700° F., while difficulties in main-

taining the hydroxides in liquid phase are sometimes encountered at temperatures between about 325 and about 400° F., even though eutectic mixtures are employed, and therefore temperatures of from about 400 to about 650° F. are preferred for carrying out the process.

The contact time employed in carrying out the process may range from a few minutes to about 20 hours, depending upon the particular oil being treated and the treating conditions employed. It has been found that the contaminants can be readily removed from some oils in a very short time and that more extended contacting is required to achieve equivalent results with other oils. In general a contacting time of from about 1 to about 16 hours has been found adequate. Any of the conventional liquid-liquid contacting methods may be employed.

In a particularly preferred embodiment of the invention, the oil from which metallic contaminants are to be removed is contacted with the alkali metal hydroxide in the presence of oxygen gas. It has been found that the addition of oxygen during the treating step of the process results in a surprising increase in the amount of contaminants removed when the oil is subsequently filtered and/or water washed. Although the reason for this surprising increase in effectiveness when oxygen is added is not fully understood, one explanation for the phenomenon may be that the oxygen reacts with unsaturated side chains on the organo-metallic molecule to form carboxylic acid groups which are then free to react with the hydroxide, although this has not been verified. The amount of oxygen employed does not appear to be highly critical and may be varied over a considerable range. Generally it is preferred to supply the oxygen by bubbling air or a similar oxygen-containing gas through the oil during treatment with the fused hydroxide but other contacting methods may also be employed. When air is employed as the oxygen source, air rates of from about 1 to 1500 standard cubic feet per barrel of oil may be used. If pure oxygen is used, very low rates are permissible. Spargers, distribution plates or other conventional means may be employed to promote contacting of the oxygen and the oil.

In a further preferred embodiment of the invention, the oil from which metallic contaminants are to be removed is subjected to a thermal pretreatment prior to being contacted with the fused alkali metal hydroxide, it having been found that such a pretreatment substantially increases the amount of the metallic contaminants removed by the process. This pretreatment, referred to as heat soaking, is preferably carried out at temperatures between about 300° F. and about 900° F. in order to avoid substantial thermal cracking of the oil. Higher temperatures may be also utilized but in that case the yield of treated oil will be appreciably decreased. The thermal pretreatment may extend over a period ranging from a few minutes to about 72 hours, depending upon the particular properties of the oil being treated and the temperature conditions employed. Heat soaking at about 650° F. to 750° F. for about 3 to about 12 hours has been found to be highly effective for increasing the removal of metallic contaminants and therefore such treatment is preferred.

Physical separation of the modified contaminants from the treated oil may be carried out by filtering, centrifuging or settling; by water washing; or by a combination of these methods. A combination of settling and water washing has been found to be particularly effective and is therefore preferred.

The exact nature and object of the invention can be more fully understood by referring to the accompanying drawing and the following detailed description of a specific embodiment of the process.

Referring now to the drawing, a hydrocarbon oil including constituents boiling in excess of about 1000° F. is introduced into the system through line 1 into distillation zone 2. The distillation zone may comprise an atmospheric pipe still, a combination of atmospheric and vac-

uum towers or other conventional distillation equipment. The feed is fractionated in tower 2 and low boiling fractions, light gases, naphtha, kerosine and heating oil may be taken off through lines 3, 4, 5 and 6. A heavy gas oil 5 may be withdrawn through line 7 and a residual fraction having an initial boiling point of about 1000° F. is taken off as a bottoms product through line 8. The residual bottoms product is passed through line 9 and if desired, may be combined with the heavy gas oil diverted through 10 line 10. Although the metallic contaminants are not present in significant quantities in oils with final boiling points below about 1000° F., the process does not adversely affect such lower boiling oils. Because of difficulties in handling the high viscosity residua boiling 15 wholly above 1000° F., it may be desirable to include lower boiling oils in the feedstream or to dilute the high boiling residua with suitable hydrocarbon solvents such as hexane, naphtha, or the like. The oil transferred through line 9 is fed into contacting tower 11 which is preferably a tower of the spray type wherein the oil is introduced into a downflowing stream of caustic or other alkali metal hydroxide, although contacting vessels of other types may also be employed.

The caustic is introduced into the system through lines 25 12 and 13 and passes through heat exchanger 14 where it is heated to the contacting temperature of from about 400 to about 700° F. The heated caustic then passes through line 15 into contacting tower 11. The mixture of oil and caustic thus formed passes downwardly out 30 of the contacting tower through line 16 and into reactor 17. Air or other oxygen-containing gas is introduced into the system through line 18 and may be heated in heat exchanger 19 if desired. The gas stream passes through line 20 and is bubbled upwardly through the mixture of oil and caustic in reactor 17. Following the introduction of the air, the mixture of caustic and oil is transferred through line 21 into holding drum 22. The contacting period in reactor 17 may vary from about 1 to about 5 hours or more and the residence time in holding 35 drum 22 will normally extend from about 1 to about 15 hours. In some cases, however, it has been found that the use of a holding drum is unnecessary and the oil and caustic may be passed directly from the reactor into the separation system. Gas and entrained air reaching 40 the top of reactor 17 is passed through line 23 and cooler 24 and then introduced into knockout drum 25. Gases are vented overhead from the knockout drum 26 and liquids are passed through line 27 into the holding drum.

The mixture of oil and caustic withdrawn from holding 45 drum 22 is transferred through line 28 into settler 29. An upper predominantly oil phase and a lower predominantly caustic phase are formed in the settler. The oil phase containing some caustic is passed through line 30 into primary washing zone 31 where it is contacted with water introduced through line 32. Water and oil are transferred from the washing zone through line 33 into an electrostatic precipitator 34. Due to the electrostatic 50 field existent in the precipitator, any emulsion which may have formed collapses and separate oil and water phases are formed. The oil phase is passed through line 35 into a secondary washing zone 36. The water phase is withdrawn from the precipitator and passed through line 37 to still 38. In the still, water is evaporated and taken 55 overhead through line 39 to condenser 40, while caustic is withdrawn from the bottom of the still and recycled through line 41 to the caustic feed lines 12 and 13. Temperature conditions in line 41 are controlled so that the caustic remains in the fused state. The water condensed in condenser 40 is passed through line 42 and, together with fresh water introduced through line 43, is introduced 60 into the secondary washing zone 36. The mixture of oil and water formed in the secondary washing zone is withdrawn through line 44 and passed to settling zone 45. The oil in the mixture separates out as an upper phase and is withdrawn as product through line 46 and the lower water 65 through line 47.

phase containing traces of caustic is withdrawn through line 47 and discarded.

The caustic phase formed in settler 29 is withdrawn therefrom through line 48 and passed into a primary sludge extractor 49. In the sludge extractor the caustic phase is washed with naphtha, hexane, heptane or a similar low boiling, highly paraffinic solvent introduced through line 50. The used solvent is withdrawn from the sludge extractor through line 51 and introduced into stripper 52. Solvent is taken overhead from the stripper through line 53 and recycled to the feed solvent stream in line 50. Oil washed out of the caustic by the solvent is recovered as a bottoms product from stripper 52 through line 54. This oil is predominantly free of metallic contaminants and may be blended with the product oil recovered through line 46.

The caustic phase from sludge extractor 49 is withdrawn through line 55 and passed to a secondary sludge extractor 56 where it is contacted with a highly aromatic solvent such as benzene, toluene, xylene or the like introduced through line 57. The spent aromatic solvent is withdrawn from the sludge extractor through line 58 and introduced into stripper 59, where the aromatic solvent is stripped from the oil washed out of the caustic and recycled through line 60 to the aromatic solvent stream in line 57. Oil from the bottom of the stripper

form; and similar procedures. These and still other modifications which may be made in the process will be apparent to those skilled in the art.

The process of the invention may be further illustrated by reference to results obtained in a series of tests wherein heavy, metals-containing oils are treated with alkali metal hydroxides in the manner described above.

EXAMPLE 1

In order to demonstrate the removal of metallic contaminants from high boiling hydrocarbon oils, heavy crude oils and residua containing metallic contaminants in high concentrations were treated with a fused eutectic mixture consisting of 60% potassium hydroxide and 40% sodium hydroxide at temperatures of from 500 to 700° F. The treating was carried out in a stainless steel reaction vessel equipped with an agitator to provide good contact between the oil and fused alkali metal hydroxides. The alkali metal hydroxide-to-oil ratios used ranged from 0.25/1 to 0.9/1. Following separation of the oil and hydroxide phases by decantation or filtration, the oil was water washed. The vanadium contents of the washed oil were determined and compared with those of the untreated oils. The effect of these treatments is shown in Table I.

Table I
REMOVAL OF METALLIC CONTAMINANTS FROM HIGH BOILING OILS BY TREATMENT WITH ALKALI METAL HYDROXIDES

Feed Stock	Vanadium Content, p.p.m.	Sulfur Content, Percent	Treating Temp., °F.	Treating Time, Hrs.	Hydroxide-to-Oil Ratio	Oil Yield, Percent	Vanadium Removal, Percent	Sulfur Removal, Percent
Heavy Residuum	385	2.7	700	3	1 0.9/1	73	100	50
Heavy Reduced Crude	390	2.8	650	3	1 0.9/1	73	100	40

Heavy Residuum	385	2.7	500	16	0.25/1	96	55	10

¹ 10% phenol on caustic added in these runs.

contains appreciable quantities of the metallic contaminants and is therefore recycled through line 61 to the feed stream to contacting tower 11. The caustic withdrawn from the secondary sludge extractor contains appreciable quantities of the metallic contaminants. In order to maintain these at an acceptable level, a portion of the caustic is purged. The major part of the caustic is recycled through line 62 to the caustic feed line 12 and a minor proportion is withdrawn as purge through line 63.

Although the process of the invention has been described above in terms of using caustic and air as the treating agents, it will be understood that the invention is not so limited and that other alkali metal hydroxides and eutectic mixtures and other oxygen-containing gases in addition to air may be used. Solutizers such as phenol may be employed to improve contacting of the oil and caustic and are often beneficial. In some cases it may be advantageous to heat-soak the oil to be treated or to employ the process in combination with other processes effective for the removal of metallic contaminants from hydrocarbon oils. Other permissible modifications in the process described include the recycling of the caustic phase without solvent washing; the use of alcohol solutions, dilute mineral acids and carbon dioxide as emulsion breakers in place of an electrostatic precipitator; the carrying out of the air oxidation and soaking steps simultaneously; the use of a light quench oil to reduce solubility of the modified contaminants in the oil and hydroxide and permit their more rapid removal by filtration, centrifugation, settling or the like; the use of carbon dioxide following the hydroxide treatment to convert inorganic metal compounds in the oil to the less soluble carbonate

The data above demonstrate that the metallic contaminant content of petroleum residua can be significantly reduced by treating the residua with alkali metal hydroxides and thereafter filtering and water washing the treated oil. The effect of the treating temperature upon vanadium removal and upon the yield of treated oil is clearly shown by the data in the table. Although the amount of vanadium removed was somewhat lower at temperatures of 600° F. and below, the yield of treated oil recovered at such temperatures was 95% or higher, as compared to yields of only 73% at the higher temperatures. The amount of metals removed can be considerably improved by the addition of oxygen to the oil-hydroxide mixture and therefore it is preferred to treat in the presence of oxygen at temperatures between about 400 and 600° F. The data also illustrate the effectiveness of the process for the removal of sulfur compounds from the oil. Such sulfur compounds are mostly thiophenic in nature and are not removed by well known treatments involving aqueous caustic.

EXAMPLE 2

In a second series of tests, samples of a heavy crude oil containing metallic contaminants particularly difficult to remove were treated with a fused eutectic mixture of sodium hydroxide and potassium hydroxide in a manner similar to that in the preceding example, except that the samples were air blown with 0.1 to 0.3 s.c.f. of air per pound of oil during treatment with the fused hydroxides. Treatment of this oil without air blowing had been found not to remove any of the vanadium from the oil. The effect of the air blowing on vanadium removal is shown in Table II below.

Table II

EFFECT OF AIR UPON METALS REMOVAL BY TREATMENT WITH ALKALI METAL HYDROXIDES

Feed Stock	Vanadium Content, p.p.m.	Sulfur Content, Percent	Treating Temp., °F.	Treating Time, Hrs.	Air Blowing	Hydroxide-to-Oil Ratio	Oil Yield, Percent	Vanadium Removal, Percent	Sulfur Removal, Percent
Crude	430	4.0	450	4	No	0.25	~100	0	10
Do	430	4.0	450	4	Yes	0.25	~100	60	15
Do	380	2.7	700	3	Yes	1.0	~65	99	61
Do	430	4.0	700	3	Yes	1.0	>50	95	46
Do	430	4.0	750	3	Yes	1.0	<50	Coke	Coke

¹ 10% phenol on caustic added to these runs as a solutizer.

The data in Table II clearly demonstrate the surprising effect of oxygen upon the removal of metallic contaminants from oils boiling above 1000° F. by treatment with fused alkali metal hydroxides. The contaminants in the particular crude treated were exceptionally difficult to remove and were not affected at all by treatment with fused hydroxides in the absence of oxygen. Air blowing during the run permitted the removal of about 60% of the vanadium present without any appreciable yield loss. The data also illustrate again the effect of treating temperature upon metals removal and oil yield. Thermal cracking at the 700 and 750° F. treating temperatures was severe and reduced oil yields seriously.

EXAMPLE 3

Tests on crude oils and residua containing metallic contaminants and similar to those treated in the preceding examples were carried out by treating with solid sodium hydroxide at room temperature. It was found that no metals were removed under these conditions. Similar tests wherein the oil was treated with 10% aqueous caustic at 650° F. showed that only minor amounts of the metals, below 10% in every case, were removed. These results clearly demonstrate that treating with solid or aqueous alkali metal hydroxides does not achieve the results of the present invention.

EXAMPLE 4

In order to demonstrate the necessity for a separation step following treatment with fused alkali metal hydroxides in accordance with the invention, a heavy residuum boiling well in excess of 1000° F. and containing 385 p.p.m. of vanadium was treated with a fused eutectic mixture of sodium and potassium hydroxide at a temperature of 500° F. The treated oil was then filtered through a Gooch-type asbestos filter mat and it was found that 22% of the vanadium originally present had been removed. The filtered oil was then water washed and it was found that the vanadium removed had been increased to 55%. It is therefore obvious that simply treating residua with fused alkali metal hydroxides does not remove the metals from the oil. Because of the extremely high boiling range of the residua in which the metallic contaminants are concentrated and the fact that refinery distillations, even at high vacuum, are limited to overhead temperatures equivalent to about 1000° F. to 1050° F. at atmospheric pressure, distillation of a reduced crude or residuum following treatment with fused caustic or a similar alkali metal hydroxide does not permit separate recovery of the metals and the oil. It is essential that the oil be subjected to filtration, water washing or a similar step following treatment with the fused alkali metal hydroxide if metallic contaminants are to be removed from the oil.

EXAMPLE 5

Two samples of heavy residuum, one of which had been heat soaked as described earlier, were treated with a fused eutectic of sodium and potassium hydroxides at 500° F. in order to determine the effect of the heat soaking upon the removal of metallic contaminants. The treatment was

carried out in the absence of air blowing in the manner described in Example 1 and was followed by filtration and water washing. The results obtained are shown in the following table:

Table III
EFFECT OF HEAT SOAKING UPON METALS REMOVAL BY TREATMENT WITH FUSED ALKALI METAL HYDROXIDES

Feed Stock	Treating Temp., °F.	Vanadium in Feed, p.p.m.	Percent Vanadium Removal	
			By Filtration	By Filtration and Water Washing
Heavy Residuum	500	385	22	55
Heat Soaked Heavy Residuum	500	400	44	75

It is apparent from the above data that heat soaking of the residuum had a surprisingly beneficial effect upon the removal of metals therefrom and permitted the recovery of product oil having a substantially lower metals content than that recovered without the heat soaking step.

What is claimed is:

- An improved process for removing metallic contaminants from a hydrocarbon oil boiling above about 1000° F. which comprises treating said oil with a fused alkali metal hydroxide at a temperature of from about 325 to about 700° F. and thereafter water washing the treated oil to remove therefrom modified metallic contaminants.
- A process as defined by claim 1 wherein said oil is contacted with said fused alkali metal hydroxide in the presence of oxygen.
- A process as defined by claim 1 wherein said fused alkali metal hydroxide is a fused eutectic mixture of sodium hydroxide and potassium hydroxide.
- A process as defined by claim 1 wherein said oil is contacted with from about 0.01 to about 2 volumes of said fused hydroxide per volume of oil.
- A process as defined by claim 1 wherein said oil is heat soaked prior to treatment with said fused alkali metal hydroxide.
- An improved process for removing innate metallic contaminants from a hydrocarbon oil at least a portion of which boils above about 1000° F. which comprises contacting said oil with a fused alkali metal hydroxide at a temperature of from about 325 to about 700° F., separating said fused hydroxide and said oil, and thereafter water washing said oil.
- A process as defined by claim 6 wherein said oil is treated with said fused alkali metal hydroxide at a temperature between about 400 and about 650° F.
- A process as defined by claim 6 wherein said alkali metal hydroxide is fused caustic.
- A process as defined by claim 6 wherein said fused hydroxide contains a solutizer.
- A process as defined by claim 6 wherein said oil is heat soaked at a temperature of from about 300 to 900° F. before being treated with said fused hydroxide.

11. An improved process for removing innate metallic contaminants from a hydrocarbon oil at least a portion of which boils above about 1000° F. which comprises admixing said oil with from about 0.01 to about 2 volumes of a fused alkali metal hydroxide at a temperature of from about 400 to about 650° F., air-blowing the mixture at a temperature of from about 400 to about 650° F., separating said hydroxide from the oil, removing modified metallic contaminants from the oil by water washing, and recovering an oil of substantially reduced metals content.

12. A process as defined by claim 11 wherein from about 0.1 to about 1 volume of fused hydroxide is admixed with said oil.

13. A process as defined by claim 11 wherein said fused hydroxide is a eutectic mixture of sodium hydroxide and potassium hydroxide containing a minor amount of phenol as a solutizer.

14. A process as defined in claim 6 wherein said oil is contacted with about 0.01 to about 2 volumes of said fused alkali metal hydroxide per volume of oil.

15. A process as defined in claim 6 wherein said oil is contacted with said fused alkali metal hydroxide in the presence of oxygen.

16. An improved process for removing metallic contaminants from a hydrocarbon oil at least a portion of which boils above about 1000° F. which comprises con-

tacting said oil with a fused alkali metal hydroxide at a temperature of from about 325 to about 700° F. and thereafter separating modified metallic contaminants from the treated oil at least a portion of which boils above about 1000° F.

17. A process as defined by claim 16 wherein modified metallic contaminants are separated from said treated oil by filtering the oil.

18. A process as defined by claim 16 wherein modified metallic contaminants are separated from said treated oil by centrifuging the oil.

19. A process as defined by claim 16 wherein modified metallic contaminants are separated from said treated oil by settling the oil.

20. Process as defined in claim 19 wherein the oil after settling is water washed to remove therefrom additional modified metallic contaminants.
